197,880

RAZOR HOLDER

Alan Rubin, 104 Chadwick Drive, Charleston, S.C.

Filed Aug. 14, 1963, Ser. No. 76,213

Term of patent 14 years

(Cl. D4—3)

FIG-1

FIG-2

FIG-3

FIG-4

FIGURE 1 is a perspective view of a razor holder embodying my new design;

FIGURE 2 is a perspective view thereof as viewed from a direction opposite to that of FIGURE 1;

FIGURE 3 is a side elevational view thereof; and

FIGURE 4 is a front elevational view thereof.

I claim:

The ornamental design for a razor holder, substantially as shown and described.

The elements shown in broken lines in FIGURES 3 and 4 are included for illustrative purposes only.

References Cited in the file of this patent

UNITED STATES PATENTS

D. 154,437 Spano ----- July 5, 1949
2,968,408 Weidt ----- Jan. 17, 1961

OTHER REFERENCES

House Beautiful, May 1949, page 75, Sheldon Plastic Sales Co. shave rack.